UNITED STATES PATENT OFFICE.

OTHO M. OTTE, OF JAMESTOWN, NEW YORK.

AUTOMOBILE-LAMP.

1,301,162.

Specification of Letters Patent. Patented Apr. 22, 1919.

Application filed February 26, 1917. Serial No. 150,887.

To all whom it may concern:

Be it known that I, OTHO M. OTTE, a citizen of the United States, residing at the city of Jamestown, in the county of Chautauqua and State of New York, have invented certain new and useful Improvements in Automobile-Lamps, of which the following, taken in connection with the accompanying drawings, is a specification.

10 The invention relates to lamps for vehicles and similar purposes wherein it is desired to throw the light a long distance; and the object of the improvement is to provide a light within a reflector at the 15 end of a cylinder and novel means by which the light is controlled, the controlling means consisting of a lens within said reflector and pyramidal concentric tubes or barrels in said cylinder and reflector, the light being supported from the center of the smaller 20 portion of said compound reflector and in spaced relation thereto and to said lens and tubes; and the invention consists in the novel features and combinations hereinafter 25 set forth and claimed.

In the drawings, Figure 1 is a vertical diametral sectional view of the lamp from front to rear showing the construction and arrangement of the same and showing in 30 dotted line the lines of the reflected light rays. Fig. 2 is a front elevation of the lamp showing the concentric tubes or barrels supported upon radial cross wires. Fig. 3 is a sectional view of the lamp at line 35 X—X in Fig. 1 showing the lens in front of the light and the adjustable supporting wires for the same. Fig. 4 is a perspective view of the dish-shaped lesser portion of the compound reflector. Fig. 5 is a perspective 40 view of the cap for the rear opening in the outer shell over the lesser reflector portion showing the screw threaded flange for attachment in the shell of the reflector. Fig. 6 is a sectional view at line Y—Y showing 45 the alternate deflection of the supporting wires to hold the tubes without rattling. Fig. 7 is a sectional diagrammatic view similar to Fig. 1 with a longer cylindrical portion.

50 Like characters of reference refer to corresponding parts in the several views.

The numeral 10 designates the outer shell or casing of a parabolic or semi-ellipsoidal reflector on the end of a cylinder, which 55 casing is preferably made of thin sheet metal with open ends, the front end being

open the full diameter of the shell for the reception of the glass 11 which is held in place by means of the sheet metal rim 12 with the rubber gasket 13 beneath the same 60 against the spacing ring 14 within the mouth of the shell 10. The glass 11 is used merely to shut out dust, mud or dirt of any kind.

The ring 14 spaces the outer shell 10 from 65 the inner reflector shell 15 which is made in the parabolic shape from the end 10' of the cylindrical portion 15' substantially the same as the outer shell 10, and sufficiently smaller to permit being supported within 70 the outer shell 10, being held in place by means of the spacing ring 14 near the front end and spacing ring 16 near the rear end.

The inner reflector 15 is a continuation 75 of the cylindrical portion and is parabolic or semi-ellipsoidal shaped and has a round opening in the rear end into which is fitted the spherical reflector 17, the outer edge 18 of the reflector 17 being sprung or turned into a curved circular flange 19 to hold the 80 reflector 17 firmly in position upon and so related to the parabolic reflector 15 as to its interior reflecting surface that the greatest radii of the smaller reflector 17 is less than the smallest radii of the greater reflector 15, the major and minor reflectors being shaped to receive each other in continuous refracting surfaces. The reflector 17 forms a part 85 of an ellipse, one focus of which is at 27 and the other in the source of light. 90

An electric light 20 is mounted in a suitable holder through the center of the small reflector 17 and has the connecting wires 21 and 22 leading therefrom to the source 95 of electrical power. The light 20 is placed on the reflector 17 so that the center or main point of the light is at such a point as will best be reflected by the two reflectors in their relation to one another and to the other controlling elements. 100

A lens 23 is supported a spaced distance in front of the light 20 preferably by a ring 24 and wires 25 which extend through the reflector shell 15 and are adjustably held in place by means of screw nuts 26 on 105 the outer ends of the wires 25, a sufficient number of wires 25 being provided to hold the ring 24 and lens 23 firmly in the centered position. The light collecting field of the lens 23 approximately equals the 110 diameter of the light collecting field of the smaller reflector 17 so that the reflected light

from the reflector 17 will be brought to focus at light 27 at a spaced distance between the true source of light 20 and the lens 23. The reflected light will thus pass 5 through the lens 23 in the same general direction as the direct rays of light, being complementary to and in addition to the direct rays passing through the lens 23 and thereby bringing all the rays of this portion 10 of the light into line parallel with the shaft of reflected light.

The rays of light are further confined and directed in a straight shaft and defects in the lens 23 and reflectors 15 and 17 are corrected by means of a plurality of parallel 15 concentric tubes or barrels 29 of any desired lengths, which extend in spaced relation around a common axis which is represented by the dotted line 28. The tubes 29 are 20 preferably supported parallel to one another and substantially equidistant from one another in pyramidal or conical form and gradually enlarging circles with the longest tube at the center, extending a short spaced 25 distance in front of the lens 23, and the largest and shortest tube 29 on the inner periphery of the cylindrical portion of the parabolic reflector 15 thereby forming a pyramid or cone of concentric tubes. The 30 pyramidal structure of the tubes 29 allows free space for the use of the parabolic reflector portion from the end of the cylindrical portion to the reflector 17 to reflect the light through the tubes 29.

35 The concentric tubes 29 in addition to assisting in the control of the rays of light are non-reflecting and protect the vision of approaching drivers and passers-by, and for this reason a larger number of the tubes 29 40 are used than would otherwise be necessary so that any slight deviation from the direct path of the shaft of light will give this much needed protection.

The tubes 29 are supported in their concentric spaced relations by means of light 45 cross wires 30 and 31 which extend from the central tube 29 to the cylinder and reflector 15. The light wires 30 and 31 are preferably made of tough strong metal and are 50 attached to the reflector 15 by passing through the same and being turned to one side with a small portion of solder thereon which holds the end firmly in position. The wires 30 and 31 are preferably inserted 55 through the concentric tubes 29 with alternate deflection, as shown in Fig. 6. A pair of wires 30 or 31 are deflected in opposite directions through the deflected openings in the tubes 29 so that they draw against one another, thereby holding firmly upon the tubes 29 and keeping them in position as desired with a certain amount of tension on the wires 30 and 31 so that there is no danger of the tubes rattling or being 60 displaced.

The wires 30 and 31 may be inserted in radial line, as shown in Fig. 2, without departing from my invention. In such case, however, each of the points of passage through the tubes 29 should receive a small 70 drop of solder to prevent any looseness or rattling of said tube. The alternate deflection of the wires 30 and 31 overcomes all of this work and holds the tube more firmly in position and at much less cost of manufacture. More wires 30 and 31 may be used when it is necessary to support tubes 29 of greater length than those shown in Fig. 1.

The small opening in the rear end of the casing 10 through which the lesser reflector 80 17 is inserted is closed by means of a cap 33 which is screwed into the sheet metal thread 36 by means of the projecting handle 34, a gasket 35 being placed beneath the overlapping edge of the cap 33 in the screw 85 joint to prevent any rattling in said joint. It is apparent that the cap 33 can be easily removed by unscrewing the same thereby opening the approach to the light 20 and reflector 17 for the adjustment or renewal 90 of the same.

The field of the shaft of light is indicated by the double pointed arrow 32 and the dotted lines leading to the same, which dotted lines include all the rays of light 95 from the light 20. All the direct rays from the light fall upon the lens and reflectors and no direct rays of light pass beyond the confines of the walls of the lamp so that all the light is projected in one general direction.

The direction of the rays of light within the domed or parabolic shaped compound reflector is indicated in Fig. 1 by dotted lines which show the focus 27 for the rays 105 reflected on the smaller reflector 17 and the definite areas of reflection through each cylinder 29 from the larger reflector 15. The area of reflection of every sub-dividing cylinder is definite and separate from the other 110 though the central line of the areas coincide. The lens 23 is so placed as to curtain and shield all oblique rays of light from entering said cylinders except after being controlled and brought parallel to the common 115 axis of the major and minor cylinders.

The source of light is as near a single point as possible and so placed that the rays therefrom strike the surface of the parabolic reflector so that the angles of reflection are 120 equal, in order to reflect the rays of light parallel through the cylinders.

Accordingly, the concentric cylinders used in the control of the light are likewise diminished as to length thus affording 125 the necessary space which should be allowed for the parabolic reflector 15, in combination with said cylinders so as to equalize the volume of light in both the central and outer cylinders.

The aim sought is elimination of diffusion of light resulting from imperfection of surface in the reflectors and from the fact that the source of light supply is not a point, for an electric lamp or other light as used today must have magnitude or breadth to produce candle power. Accordingly by limiting as greatly as possible the diffused light, a light of much less candle power may be used for giving the same amount of light, for not only all direct rays are controlled but all light energy expended in diffusion has been added to the controlled rays, thereby increasing the efficiency and brilliancy of the light.

It is obvious that the rays of light passing through the cylinders parallel with the sides of the same and at no point coming in contact with said cylinders control the light from the lamp so that the sides of the cylinders are not used for reflecting purposes but are used solely for control and guidance in such form that they also provide a shield or curtain preventing the lamp and reflector being seen except when the sight allows the parallel rays to be received by the eye.

There is complete circulation in the lamp construction. The heat rises from the lamp 30 and goes forward against the glass 11 which cools it. The tubes 29 are spaced from the inner face of the glass 11 a short distance, as shown at 37, thereby permitting the cooled air to drop to the lower side as soon as cooled by the glass 11, for it is apparent that as the lamp is forced through the air the glass 11 is cooled and will almost instantaneously cool the heated air as it rises from the lamp 20. As the air drops to the 40 lower portion of the lamp through the space 37 it passes back and up past the lamp 20 again, thereby causing a continuous circulation of air in the shell 15 as soon as the lamp 20 is lighted.

45 I claim as new:—

1. In combination with a reflector having a closed rear end and a continuous reflecting surface, a source of light in front of said closed rear end, a cellular structure in 50 the reflector, said structure being of pyramidal formation with its apex adjacent the source of light, and a lens arranged between the source of light and apex of the structure and aligned with each.

55 2. A reflector comprising a cylindrical barrel having a dome-shaped end with a reflecting inner surface, a light within said

dome-shaped end, a lens, and a plurality of tubes filling said cylindrical barrel to aid in controlling the reflected rays of light, said 60 tubes being arranged so as to be shielded from all direct rays of light.

3. A reflector comprising a cylindrical portion, a compound reflector portion attached to said cylindrical portion, a plurality of cylindrical barrels supported within said cylindrical portion, the shortest of said barrels the length of said cylindrical portion and the central barrel of greater length extending nearer the light, the remaining 70 barrels being graduated as to length to form a pyramidal structure, and a lens to the rear of the longest barrel.

4. A reflector comprising a cylindrical barrel portion and a compound reflector portion, a plurality of concentric barrels in said cylindrical barrel portion, said concentric barrels supported in spaced relation by a plurality of radial wires, said radial wires oppositely deflected in alternate concentric 80 barrels to draw upon one another and hold said concentric barrels firmly in position.

5. The combination of a parabolic reflector and source of light therewithin with a cellular structure of pyramidal shape with 85 the apex nearest said source of light and a common axis between said pyramidal structure and source of light, the walls of the cells being parallel each to the other and to the common axis and a lens to the rear of 90 said structure.

6. The combination with a reflector parabolic in part, a lens supported in said reflector, a source of light spaced between said lens and the closed end of said reflector, a 95 plurality of concentric barrels with the longest barrel nearest said lens and the shortest barrel at the outer rim of said reflector, said concentric barrels having parallel sides and equidistant spacing and graduated as to length between said shortest barrel and said longest barrel to form a pyramidal structure within said reflector to receive and not retard all parallel reflected rays of light through said barrels from said 100 parabolic reflector, said tubes being shielded from all direct rays.

In testimony whereof I have affixed my signature in the presence of two witnesses.

OTHO M. OTTE.
